COMPRESSIBLE FASTENER

Joseph C. Lang, Pittsburgh, Pa., assignor to Bocjl Corporation, Pittsburgh, Pa., a corporation of Delaware

Application June 16, 1945, Serial No. 599,817

5 Claims. (Cl. 85—49)

1

This invention relates to fasteners for joining pieces of wood or wood-like material and to a method of forming structures which utilize the same.

In many structures, intersecting boards are required to be joined together at several places along their length. This is true, for example, in shipping crates which are made up of wooden frame members carrying panels of heavy cardboard or fiberboard. Such crates are commonly used in the shipment of heavy consumer goods, as refrigerators, radios, washing machines, etc. In such crates a side panel may intersect a top or bottom or end panel along substantially the full dimensions of the two panels. The common practice at the present time is to nail the panels together, but the holding power of the nails is not always adequate; frequently the lumber which is not for the most part prime lumber, is split. Crates of this kind are relatively expensive, and in many centers there are reclaiming services. The use of nails is likely to cause breakage in opening the crates, rendering them less acceptable for reuse.

The present invention provides a fastener or fastening which is eminently satisfactory for this and like purposes; which per pound of metal holds more than nails, requiring relatively few fasteners per crate; which is not likely to damage the crate, and facilitates opening of the crate.

To this end my invention provides a fastener having opposed claw elements that are brought into fastening relation with the two pieces of wood or other material to be connected by driving them toward each other and simultaneously shortening the overall length of the portion of the fastener that connects the opposed claw elements.

My invention may be more fully understood by reference to the accompanying drawings, in which.

Fig. 1 shows a plan view of a fastener embodying my invention and in position to be applied to two adjoining pieces of wood;

Fig. 2 is a side elevation of Fig. 1;

Fig. 3 is a view similar to Fig. 1 showing the fastener after it has been driven;

Fig. 4 is a view similar to Fig. 1 of a modification;

Fig. 5 is a perspective view of a typical crate constructed in accordance with my invention;

Fig. 6 is a perspective view of another modification;

Fig. 7 is a plan view of the fastener of Fig. 6 after it has been driven; and

2

Fig. 8 is a perspective view of another form of fastener embodying my invention and showing the manner of setting it.

In Figs. 1, 2 and 3 of the drawings, the fastener 5 is designated generally as A, and B and C designate frame elements of intersecting crate panels which may include heavy pasteboard, fiberboard, or plywood.

The fastener A may be made in a desired range 10 of sizes. It comprises, in the preferred form, a central loop portion 2 with two oppositely extending pairs of arms, 3 and 4 at diametrically opposite sides thereof. The loop may preferably be a parallelogram with the arms extending as 15 shown from the opposite diagonals. Both pairs of arms have downwardly turned ends 3a and 4a respectively, with inwardly turned portions or prongs 3b and 4b respectively, these portions being pointed as shown.

20 These arms, in effect, comprise opposite claw elements, or opposite pairs of claws. The flat arms, together with the loop, form a rigid but contractible bridge or connection. Contractility is provided by the loop 2 which may be 25 elongated on the axis transverse to the longitudinal axis of the fastener and shortened along the longitudinal axis, as will be hereinafter more fully described.

In use, the fastener is set astraddle the intersecting frame members B and C, as shown in 30 Figs. 1 and 2. Then, preferably by a special driver which exerts pressure on the claws to drive them into the wood while confining the connecting or bridge portion of the fastener flat against the wood, the fastener is set, the portions or 35 prongs 3b and 4b entering the pieces of wood downwardly from the plane of the adjoining surfaces.

After being driven or set, the fastener assumes 40 the form shown in Fig. 3, where the opposite claw elements have been forced toward each other with the prongs or hooks entering the wood and the loop 2 has been elongated on its transverse axis and shortened in a longitudinal direction. The 45 fastener is made of relatively heavy metal, so that when it has been shortened in this manner it will withstand enormous tensile strains, much beyond the holding factor required for the purpose, before it will stretch apart to allow the 50 wooden members to separate.

To open a crate which has been secured with these fasteners, it is only necessary to cut the fasteners along the line x—x in Fig. 3. This may be done with a cold chisel or a suitable nipper. 55 When the fastener has been cut in this fashion,

the pieces of wood will separate and the parts of the fastener which are attached thereto may be readily removed from the wood without damage to the wood.

The fastener as shown in Figs. 1 to 3 may conveniently be formed from a narrow ribbon of metal, slit in a longitudinal direction, and then expanded or stretched transversely of the slit to form a succession of loops. Alternate loops form the centers 2 of the fasteners while the other loops are cut transversely to form the arms 3 and 4. This method is described in my co-pending application Serial No. 554,349, filed September 16, 1944, now Patent No. 2,384,477 issued September 11, 1945.

Fig. 4 illustrates a similar fastener formed from wire. Two pieces of wire 10 and 11 are twisted about each other at spaced points 12 forming a central loop 13 and diverging arms 14 and 15. The arms 14 and 15 are turned downwardly and inwardly at 16 and 17, respectively, the parts 16 and 17 providing the inwardly turned prongs. If desired the twists 12 may be spot welded.

Fig. 5 illustrates a typical crate construction made up of top and bottom panels P, side panels P1 and end panels P2. These panels comprise wooden frame members, as previously described, and sheathing sheets of pasteboard or fiberboard. As illustrated the frame members which intersect at right angles are joined by the fasteners A. Two or three fasteners along the intersecting members are usually sufficient.

In the modification shown in Figs. 6 and 7, the fastener has but two claw elements, these being designated 25, and they are at the free ends of arms 26. The two arms are oppositely offset at 27, and 28 is a diagonal connecting portion, forming a zig-zag connection. When pressure is applied to the two claw elements, they are forced into the wood, as indicated in Fig. 7, the offset portions 27 being folded in toward the longitudinal axis of the fastener. The overall length of the fastener is thus decreased by the bending of a portion of the bridge of the staple between the two claws.

In the modification shown in Fig. 8, the fastener is of X form, being illustrated as being made of wire, but it may be formed as indicated from flat strip metal. It has a central connecting portion 30 at the opposite ends of which are outwardly divergent arms 31, these arms having parallel portions 32, and on the free ends of the parallel portions are the claw or hook elements 33.

The fastener is placed on the work as heretofore described. It is then subjected to pressure against the claws while the bridge is confined to a plane. When thus squeezed, the overall length of the fastener is shortened by the angularity of the divergent arms being increased by movement in the direction of the dotted arrows shown in the drawing. Thus, again the setting of the fastener is accomplished by confining the fastener to a plane, subjecting its opposite ends to pressure, and deforming or bending part of the mid-portion or bridge of the fastener.

In all forms, the fastener has opposed claw elements and a connection which includes a por-

tion which is angular to the longitudinal axis of the fastener.

While I have illustrated and described certain present preferred embodiments of my invention it will be understood that this is by way of illustration and that various modifications and changes may be made therein.

I claim:

1. A fastener comprising oppositely extending pairs of divergent arms, each arm having a downwardly and inwardly turned hook portion thereon, and a closed loop connecting the two pairs of arms, said loop being capable of being squeezed in the direction of the length of the fastener to shorten the overall length of the fastener.

2. A fastener comprising a loop of generally parallelogram form with one of its diagonals transverse to the longitudinal axis of the fastener, and a pair of divergent arms attached to each of the two opposite corners of the parallelogram that are on the said longitudinal axis, said arms having downwardly and inwardly turned hook portions at the ends thereof.

3. A fastener comprising a loop and a pair of divergent arms attached to the metal of the sides of the loop, said arms having downwardly and inwardly turned hook portions at the ends thereof, said fasteners being integrally formed from strip metal.

4. A fastener comprising a loop and a pair of divergent arms at opposite sides of the loop, said arms having downwardly and inwardly turned hook portions at the ends thereof, said fastener being formed of two pieces of wire twisted about each other at the two sides of the loop from which the arms extend.

5. A fastener comprising a rectangular loop portion with one of its diagonals transverse to the longitudinal axis of the fastener and claw elements extending from the middle of the sides of the loop in opposite directions, the claw elements comprising arms with downwardly and inwardly turned hook portions at the ends of the arms.
